UNITED STATES PATENT OFFICE.

ISAAC SHERCK, OF FREMONT, OHIO, ASSIGNOR TO HIMSELF, WM. F. JOBBINS, OF NEW YORK, N. Y., AND GEORGE E. RAYMOND, OF COLUMBUS, OHIO.

TURBINE WATER-WHEEL.

SPECIFICATION forming part of Letters Patent No. 242,482, dated June 7, 1881.

Application filed December 17, 1880. (Model.)

To all whom it may concern:

Be it known that I, ISAAC SHERCK, of Fremont, in the State of Ohio, have invented certain new and useful Improvements in Turbine Water-Wheels; and I do hereby declare the following to be a full, clear, and exact description of the invention, such as will enable others skilled in the art to which it pertains to make and use it, reference being had to the accompanying drawings, which form part of this specification.

My invention relates to an improvement in turbine water-wheels, the object being to provide a wheel of this type in which the maximum power of the water may be utilized; further, to decrease the wear between the gate and wheel case; further, to allow of the ready adjustment and leveling of the gate, and to obviate wear and friction in its bottom; further, to provide pivoted gate-wings adapted to be automatically opened and closed by actuating the gate; further, to furnish a globe-case, in which the water may flow in a circular path completely around the wheel, and in the same direction as that of the wheel; further, to provide the casing of a wheel of such construction that access to the wheel may be readily had without disturbing or removing the stuffing-box for the wheel or gate spindles; further, to provide simple and efficient means for securing the top of the casing to the main portion thereof; further, to provide means for preventing any accidental displacement of the gate, and also take any undue strain or wear off from the worm-gear by means of which the gate is rotated; further, to provide simple and efficient connections between the gate and its rack; and with these several ends in view my invention consists in the several details in construction and combinations of parts in a turbine water-wheel, as will hereinafter be described, and pointed out in the claims.

In the accompanying drawings, Figure 1 is a view, in perspective, of a turbine water-wheel embodying my invention. Fig. 2 is a vertical section of the same. Fig. 3 is a view, in side elevation, of the wheel proper. Fig. 4 is a view, in perspective, of one of the buckets. Fig. 5 is a view, in side elevation, of the wheel-case. Fig. 6 is a horizontal section taken through the ports

of the wheel-case. Fig. 7 is a vertical section taken through the gate and wheel-case, showing the devices employed for adjusting the gate vertically. Fig. 8 is an enlarged view of a portion of the gate with the wooden bearing, serving as a laterally-adjustable bearing for the gate. Fig. 9 is an enlarged view of one of the vertically-adjustable bearings, upon which rests the bottom of the gate-ring. Fig. 10 is an enlarged view of one of the pivoted gate-wings, showing it in its open position. Fig. 11 is a similar view showing it in its closed position. Fig. 12 is a view, in perspective, of one of the pivoted gate-wings. Fig. 13 is a view, in perspective, of one of the gate-wings, and a section of a gate-ring. Fig. 14 is a detached view showing the manner of attaching the top of the globe-case to the main portion thereof. Fig. 15 is a plan view of the interior of the globe or penstock case. Fig. 16 is a plan view of the under side of the crown-plate and ring connected therewith. Fig. 17 is a plan view of the wheel, the upper portion of the globe-case being removed.

A represents the globe or penstock case. It is provided with an induction-opening, *a*, through which water is admitted to the wheel. The periphery *a'* of the case, together with the inwardly-projecting flat flange *a*², are made of a single casting.

B is the casing of the wheel C. Casing B is constructed with a horizontal flange, *b*, which rests upon the flat flange *a*² of the globe-casing, and is secured thereto by means of pivoted lugs *b'*, which latter are secured in place by means of screw-bolts *b*². Wheel-casing B is also provided with a downwardly-projecting flange, having perforated ears *b*³, to which are removably secured the opposite ends of the step-bar *b*⁴, by means of screws *b*⁵ extending through the depending ears *b*³ and flanges *b*⁶ formed on the ends of the step-bar *b*⁴.

An adjustable conical step-bearing, *c*, is inserted through the center of the step-bar, the conical end thereof entering a corresponding bearing in the lower end of the wheel-spindle C'. By raising or lowering the step *c* the wheel may be secured in any desired vertical adjustment.

Wheel-casing B is provided with any de-

sired number of vertically-adjustable bearings, B', which are located in the horizontal flange b, and serve to support the lower ring, d, of the gate D. Bearings B' are adapted to be vertically adjusted by means of screws B², which latter have pointed or wedge-shaped ends, that engage with the under sides of the bearings, whereby the latter may be raised to any desired point.

10 The object of providing adjustable bearings for the gate is to obviate the wear on the lower gate-ring and the horizontal flange of the wheel-casing. Further, the friction between the gate and casing is materially reduced, for 15 the following reason: When the gate rests upon the flange of the wheel-casing and has a continuous bearing thereon, any sand or abrasive substances that may find lodgment between the bottom of the gate and the supporting-20 flange of the wheel-casing will operate to cut and wear away the gate and casing, and also materially increase the friction between such parts, so that an undue amount of power is necessary to adjust the gate.

25 By employing vertically-adjustable bearings for supporting the gate the weight and wear are transferred upon said bearings, instead of upon the gate and casing, and when the bearings become unduly worn they may be vertically adjusted to take up for any such wear. 30 These bearings may be renewed when desired.

Should sand work in between the gate and casing it is enabled to escape without wearing the parts, as the supporting-bearings are 35 adjusted so that the gate will be slightly raised above the supporting-flange of the wheel-casing.

The top ring, d', of the gate D is provided with radially-adjustable wooden bearings D', 40 (three or more,) each of which is provided with an elongated slot, d², through which is inserted a screw, d³. The inner ends of these wooden bearings are forced in snug contact with the upper ring, d', of the wheel-case. The purpose of these wooden bearings is to take up 45 any wear between the gate and wheel-case. Should any sand find its way between the gate and wheel-case both parts will be worn, and considerable friction is the result; but by employing the wooden bearings the wear and 50 friction are materially lessened. These bearings may be made of any hard wood, and are so constructed that the ends of the grain of wood will bear against the upper ring of the wheel-case.

55 The wheel-case is provided with any desired number of inclined ports E. The rear wall, e, of each port is chambered, as at e', in order to provide ample clearance and lessen the friction of the water as it passes through the ports to the wheel.

To the horizontal flange are secured upright pivots e², equal in number to the number of ports in the wheel-case.

65 Upon each upright or vertical pivot e² is pivoted a gate-wing, F, the latter having ears e³

formed on its rear side and near its forward end. Gate-wing F is of such length that its rear end will swing around and fit against the rear wall or edge, f, of the adjacent port in the wheel-case, and when in such open position the inner surface of the gate-wing and the inclined inner wall of the port will be in alignment, thereby forming a straight chute for the passage of the water to the wheel. Each gate-wing is provided at its forward end and on its lower edge with an arm, F', which engages with the outer edge of the lower ring of the gate, said edge having notches or depressions F² formed therein. When the gate is wide 75 open the rear end of the gate-wing will fit against the rear wall or edge, f, of the port in the wheel-case, and project slightly beneath the forward edge, f', of the partition F³ of the gate. In this position the arm F' will engage 80 with the smooth or circular portion f² of the edge of the gate-ring, and the gate-wing will be securely held against displacement. By turning the gate so as to contract the openings 85 of the ports the rear ends of the gate-wings 90 are retained in place by means of the arms F' fitting against the edge of the lower gate-ring. When the gate is completely closed the arm F' falls into one of the notches or depressions 95 F², thus allowing the rear end of the gate-wing F³, and thus form a complete cut-off. This 100 form of pivoted gate-wings is most efficient in operation, as they enable the ports to be opened or closed and preserve the form of the chute under all degrees of adjustment.

The gate-wings are securely retained against accidental displacement, and the construction and arrangement of parts are simple, of small initial cost, not liable to disarrangement, and 105 easy of operation.

The upper and lower gate-rings are beveled upwardly from their outer to their inner edges, for the purpose of directing the flow of water upwardly against the buckets of the wheel, and thus assist in sustaining the weight of the wheel and lessening its friction on its bearings, and also obviate the tendency of the water to slip on the buckets.

Wheel C is provided with buckets G, which 115 are secured at their upper ends to the crown G' and at their inner edges to the drum G². Buckets G extend outward tangentially from the drum G², the outer ends thereof being provided with sides g, the forward edges of which 120 are made sharp, so as to constitute cutters and prevent any undue friction of the water as it strikes the sides of the bucket, but deflect the water into the buckets. The lower ends, g', of the buckets are rearwardly inclined, to form 125 an inclined downward discharge, and thereby cause the weight of the water to assist in imparting rotary movement to the wheel.

At the juncture of the vertical and rearwardly-inclined portions of the buckets there 130 is formed a horizontal surface, H, which serves to form a pocket in the bucket for holding the

water against the vertical portion of the buckets until its reaction force is utilized, and then allow the weight of the water to act on the rearwardly-inclined portion of the bucket. This particular feature in the form of the buckets I consider as of great value and importance. In the ordinary form of bucket the vertical and inclined portions are connected by a curved surface, or else the bucket is on a gradual curve from its top to its bottom; but such buckets are objectionable, owing to the fact that the water will slip on the curved portion thereof, and hence the reaction force of the water can be only partially utilized; but by providing a pocket at the lower end of the vertical portion of the bucket the water is prevented from slipping, and thus the maximum force due to the weight and reaction force of the water is utilized in imparting motion to the wheel.

The globe or penstock case is formed on a true circle, thereby insuring a continuous circular passage, H, around the gate, and thus allows the water to enter the case at right angles to the wheel and flow through the gate and be discharged into the buckets. Should there be any surplusage of water it will flow around the wheel in a true circle and mingle with the supply, thus preventing any disturbance of the flow or reaction of the current due to abutments or partitions in the casing as ordinarily constructed.

The globe-casing is constructed with a ledge or flange, H', with which engage the hooked ends i of the screw-bolts I, which are used to fasten the casing-ring J to the top of the case. The hooked bolts are first inserted in the casing-ring J and the latter placed in position when the hooked ends of the bolts are turned beneath the ledge or flange H', and the nuts H² then being turned down the casing-ring is firmly secured in place.

K is the crown-plate of the wheel-case, and is secured to the casing-ring by means of screws or bolts inserted through the lugs K', attached to the casing-ring J, and screw K², inserted through a bracket, K³, attached to the frame K⁴, in which the gate-operating devices are located. The crown-plate K is provided with a stuffing-box, L, in which is located the upper end of the wheel-spindle. This construction of casing renders it an easy matter to gain access to the wheel without removing the crown-plate K, and hence not disturbing the stuffing-box. It is simply necessary to loosen the hooked bolts I and screws K' K², and lift the casing-ring J, with its gate-operating mechanism attached thereto, and thus render the wheel and gate accessible without necessitating the removal of the crown-plate or disturbing the stuffing-box of the wheel shaft or spindle.

M is gate-rack, provided at one end with a segmental rack, m. Gate-rack M is journaled at its central portion upon the hub or stuffing-box L of the crown-plate. To the opposite

ends of the gate-rack are attached the pins N N', which extend downwardly through elongated slots n in the casing-ring and through the slide-plates O O', located beneath the elongated slots n, the lower ends of said pins entering holes o o' formed in the upper gate-ring. Slide-plates O O' are retained in place by means of keepers P P'. Thus it will be observed that the gate-rack engages with the opposite sides of the gate and distributes the power equally to the same for adjusting it. The slide-plates serve to prevent any escape of water through the elongated slots n in the casing-ring.

The pins N N', being constructed and arranged to enter holes in the upper ring of the gate, allow the casing-ring to be removed without disturbing the gate or its actuating mechanism.

Within the frame K⁴ attached to the casing-ring is journaled a worm-shaft, Q, which engages with a worm-gear, Q', mounted on a shaft, q. Pinion Q² is also rigidly secured to the shaft q, and meshes with the segmental rack m. Hence the worm-shaft being turned serves to move the gate-rack and open or close the gate, according to the direction in which the worm is revolved.

To the end of the shaft q is secured an arm, R, having an adjustable counter-weight, S, secured thereto, the purpose of which is as follows: The tendency of the gate-wings is to close, which is due to the pressure of water against them. To counteract such force and relieve the worm-shaft and gear of undue strain I employ the counter-weight S, the latter operating in opposition to the force exerted on the gate-wings. I may connect the counter-weight with the gate, so as to balance it in other positions than that shown and described—as, for instance, it may be made separate and distinct from the gate-operating mechanism and operate in connection with a rack attached to the gate.

Any suitable packing is located over the joint formed between the wheel-case and gate, and the packing is secured in place by means of clips.

I am aware that a turbine wheel is old where-in the wheel proper is located within a scroll-case, the latter being constructed with an inner and an outer case. The inner case is concentric with the wheel, and is provided with stationary guides, which extend outwardly into the water-passage of the scroll. A gate is located in the scroll and arranged so as to cut off the water from a portion of the wheel-buckets, when desired. Hence I would have it understood that I make no claim to the construction and arrangement of parts specified. In my improved wheel the globe case is concentric with the wheel-casing, and the periphery of the case is of curved form. Further, the globe-case is made independent of the wheel-case and removably secured thereto; and, again, the wheel-case is provided with a series of water-

passages, which are controlled by adjustable gate-wings, whereby all the buckets are supplied with a certain predetermined quantity of water.

5 Having fully described my invention, what I claim as new, and desire to secure by Letters Patent, is—

1. In a turbine water-wheel, buckets constructed with vertical and rearwardly-inclined portions, having a pocket formed at their point of juncture, the vertical portion provided with an outwardly-flaring side having a cutting-edge, and the rearwardly-inclined portion provided with a side of gradually-increasing width from its upper to its lower end, substantially as set forth.

2. The combination, with the wheel-case and gate-ring, of wooden bearings attached to the gate-ring and adapted to bear against the upper ring of the wheel-case, substantially as set forth.

3. The combination, with the wheel-case and gate-ring, of radially-adjustable wooden bearings attached to the gate-ring and adapted to bear against the upper ring of the wheel-case, substantially as set forth.

4. The combination, with a wheel-case, of a gate-ring provided with slotted wooden bearings and screws inserted through said bearings for securing the same in any desired adjustment, substantially as set forth.

5. The combination, with a wheel-case and gate, of vertically-adjustable bearings located in the horizontal flange of the wheel-case and adapted to support the gate, substantially as set forth.

6. The combination, with a wheel-case and gate, of bearings located in the horizontal flange of the wheel-case and pointed screws for imparting vertical adjustment to said bearings, substantially as set forth.

7. The combination, with a wheel-case and gate-ring, of gate-wings pivoted to upright pivots attached to the wheel-case, said gate-wings provided with a bearing at one end on the periphery of the wheel-case and at its opposite end on the edge of the gate-ring, substantially as set forth.

8. The combination, with a wheel-case and gate, the latter having notches or depressions in the edge of its lower ring, of pivoted gate-wings, each provided with an arm that engages the notched edge of the gate-ring, substantially as set forth.

9. The combination, with a gate having upwardly-beveled upper and lower rings, of gate-wings pivoted to the wheel-case and adapted to be automatically opened and closed, substantially as set forth.

10. The combination, with a gate and wheel-case, of gate-wings pivoted on their rear sides and near their forward ends to upright pivots attached to the wheel-case, substantially as set forth.

11. In a turbine wheel, the combination, with a globe-case having a flat flange on its under

side, of a wheel-case provided with a horizontal flange and pivoted lugs for securing the wheel-case in place, substantially as set forth.

12. In a turbine wheel, the combination, with a globe-case having a ledge or flange on its upper side, of a casing-ring and hooked bolts and nuts for securing the casing-ring to the case, substantially as set forth.

13. In a turbine wheel, the combination, with a globe-case having a casing-ring secured thereto, of a crown-plate removably secured to said casing-ring, substantially as set forth.

14. In a turbine wheel, the combination, with a casing-ring, of a crown-plate and perforated lugs attached to the ring and overlapping the plate and screws for securing the parts together, substantially as set forth.

15. In a turbine wheel, the combination, with the gate, of a gate-rack provided with pins which extend through elongated slots in the casing and enter holes in the gate-ring, and sliding plates located beneath said elongated slots, substantially as set forth.

16. In a turbine wheel, the combination, with the gate-rack, downwardly-projecting pins or lugs, and slides, of keepers attached to the under side of the casing-ring and adapted to retain the slides in place, substantially as set forth.

17. In a turbine wheel, the combination of a series of pivoted gates, a gate-rack, a counterbalance-weight, and intermediate cog-gearing, said gearing being inclosed in a frame mounted on the top of the wheel, as set forth.

18. The combination, with the gate-rack, of a worm-shaft, worm-gear, pinion, and counter-weight-lever, substantially as set forth.

19. In a turbine wheel, the combination, with the wheel, wheel-casing, and a series of adjustable gates encircling the wheel-casing, of a globe-case removably secured to the wheel-casing, said globe-case being constructed with outwardly-curved periphery and arranged concentric to the wheel-casing to form a water-passage for the water completely around the wheel-casing, said globe-case being provided with a supply-conduit arranged with relation to the wheel-case, substantially as shown and described, whereby the direction of the current entering the globe-case will be on a line intersecting the gate-wings and outside of the wheel-buckets, substantially as set forth.

20. In a turbine water-wheel, the combination, with the gate-wings, of a wheel-case provided with ports, the walls at one side being straight and in line with the gate-wings when open and the opposite sides of the ports having angular chambers formed therein, substantially as set forth.

In testimony that I claim the foregoing I have hereunto set my hand this 1st day of December, 1880.

ISAAC SHERCK.
